TUNING PEG FOR STRINGED INSTRUMENTS.

Application filed July 26, 1922. Serial No. 577,653.

Our invention relates to pegs for stringed instruments, and more particularly to means for control and maintenance of the tension of the strings thereof, and has for an object 5 to produce a device of the class described more economically and of improved efficiency.

Having reference to the drawings illustrative of a preferred embodiment of my improved peg or key, Figure 1 is an elevation of a familiar type of the stringed musical instruments to which our improved peg relates;

Fig. 2 is a partial sectional view of the 15 arm of the instrument shown in Fig. 1 with key in position;

Fig. 3 is a like sectional view of key with modified parts and connections;

Fig. 4 is a cross section on line 4—4 of 20 Fig. 2 and

Fig. 5 is a perspective view of a disassembled part.

Referring to the drawings, the numeral 1 represents an ordinary banjo in connection 25 with which our improvement is illustrated, having the head 2 in which are suitably arranged the pegs 5 of our improved structure. Upon the instrument are mounted in the usual manner the complement of strings 3 attached at their outer ends to the tuning 30 pegs 5. The peg 5 has a shaft 6 with a shouldered head or drum portion 7 preferably made integral therewith through which is the hole 4 transversely disposed for the 35 purpose of receiving and securing the end of a catgut 3. The key shaft or shank 6 has at its opposite end a thumb piece 8 having a central orifice longitudinally thereof through which extends an end of the shaft 6. 40 Into a threaded orifice at the end of the shaft 6 is adapted to fit the screw 10 upon which is the washer 9 adapted to hold the thumb piece 8 upon the shaft 6. To hold the thumb piece 8 against rotatable movement on the 45 shaft the shoe 20, shown in perspective in Fig. 5, is hollowed out to receive therein the bottom of the thumb piece through which the shaft 6 is introduced, the thumb piece 8 being firmly seated within the curved bottom 50 21 of the shoe.

An orifice 22 centrally disposed in the circular wall of the shoe 20 has parallel sides 23 which engage correspondingly flattened sides 11 of the shaft 6 which exactly fits

into the hole 22 therein (see Figs. 4 and 5). 55 The thumb piece 8 is held firmly seated in the hole of the shoe piece 20.

The shoe piece 20 has a further function in addition to that of securing the thumb piece 8 to the shaft 6, in that it presents a 60 frictional surface to the head member 2 to hold the key in the position into which it has been drawn by thumb action. But instead of having the outer face 21 of the shoe 20 rest directly upon the surface of the 65 head 2, an additional member 30 is interposed which in the preferred form shown in Fig. 2 is a raised member, being secured to the head 2 by means of screws or pin 32 through the flattened extensions 31. This 70 same member however can be replaced by an ordinary washer such as shown at 30^a of the modified form shown in Fig. 3. However, the member 30 in the form shown supplies the additional advantage of providing greater length of bearing for the shaft 6, and I accordingly employ the latter form for the 75 manifold purposes explained.

The frictional contact between the under surface 21 of the shoe cup 20, on the one 80 hand, and the top face of the piece 30 or 30^a, on the other, is rendered more serviceable by having one of the members made of brass or bronze while the other with which it comes into frictional contact is made of 85 steel or iron. Thus, in the preferred form I employ the shoe pieces of brass and the washer 30 (or 30^a) of steel.

By means of the screw 10 any desired frictional contact pressure between the surface 90 21 of the shoe piece 20 and 35 on the member 30 may be obtained. Such frictional adjustment having been secured, the thumb piece by rotation upon its axis will draw a catgut or other string member 3 to any desired 95 tension and the adjustment 10 is made sufficiently tense to hold the key in the position where it is thus drawn.

The frictional retaining parts as above described are found to work more satisfactorily 100 by introducing beneath the pieces 30 and 30^a a washer 32^a, preferably of some slightly yielding material such as leather of suitable type, as shown in Fig. 2. Thus the washers of brass or steel, as the case may be, will 105 present a more even surface to the wall 21 of the shoe piece 20.

The string is attached to the drum 7 as

has already been pointed out by passing through the transverse orifice 4, and may be secured from withdrawal by the simple means of a knot at the end. Preferably the 5 string is sufficiently long to require at least one complete rotation of the drum 7 and thereafter by continuous pressure upon the thumb piece in the direction of winding farther on to the head the string may be drawn 10 to the required tension and by reason of the screw adjustment 10 having been predetermined to hold the key against return motion, the proper tautness may be indefinitely maintained.

15 We claim:

1. In a stringed musical instrument having a frame with a peg aperture, a tuning peg passing through the aperture and having a shoulder to limit endwise movement 20 of the peg in the aperture in one direction, a transversely recessed shoe slidably and non-rotatably carried by the peg outside of the aperture, said peg having a head fitting in the recessed portion of the shoe and adjustable along the peg, and a metal friction member disposed around the peg secured to the frame adjacent the shoe.

2. In a stringed musical instrument, having a frame with a peg aperture, a tuning peg passing through the aperture and having a shoulder to limit endwise movement of the peg in the aperture in one direction a recessed shoe slidably and non-rotatably carried by the peg outside of the aperture, said 30 peg having a head fitting in the recess of the shoe and adjustable along the peg shank, a washer of a slightly resilient non-metallic material between the shoe and the frame, and a metal friction member disposed 35 around the peg shank between the washer and the shoe.

3. In a stringed musical instrument, a string adjusting peg having a shoulder adjacent one end for limiting movement of 45 the peg endwise of itself in the frame of the instrument, a thumb piece rotatable and slid- able upon the other end of the peg, a shoe slideable and non-rotatable upon the peg and having a concavity in which the thumb 50 piece is disposed, a friction member on the peg between the shoe and the frame of the instrument, and means for holding the thumb piece on the peg in said concavity and for adjusting the thumb piece and shoe 55 toward the friction member to vary the friction between the shoe and member which holds the peg in adjusted angular positions.

4. In a stringed musical instrument, a string adjusting peg having a shoulder adjacent one end for limiting movement of the 60 peg endwise of itself in the frame of the instrument, a thumb piece rotatable and slideable upon the other end of the peg, a shoe slideable and non-rotatable upon the peg and having a concavity in which the thumb piece 65 is disposed, a friction member on the peg between the shoe and the frame of the instrument, means for holding the thumb piece on the peg in said concavity and for adjusting the thumb piece and shoe toward the 70 friction member to vary the friction between the shoe and member which holds the peg in adjusted angular positions, and a washer on the peg between the friction member and the frame of the instrument. 75

5. In a tuning peg for musical instruments having a shaft adapted to be supported in an aperture in the head of the instrument, said shaft having a shoulder to limit endwise movement thereof in the aperture in one direction, and having throughout a portion of its length a flattened surface, a thumb piece rotatably mounted on said shaft, an interponent member slidably supported on said shaft and having an aperture 80 with a flattened side adapted to engage the correspondingly flattened surface of the shaft, a transversely disposed recess in the interponent member into which the thumb piece is adapted to seat and means for securing said thumb piece in said recess. 90

6. In a tuning peg for musical instruments having a shaft adapted to be supported in an aperture in the head of the instrument, said shaft having a shoulder to limit endwise movement thereof in the aperture in one direction, and having throughout a portion of its length a flattened surface, a thumb piece rotatably mounted on said shaft, an interponent member slidably supported on said shaft and having an aperture 95 with a flattened side adapted to engage the correspondingly flattened surface of the shaft, means for holding said thumb piece against rotation relatively to said interponent member said means comprising a transversely disposed recess in one of said elements, and securing the other of said elements in said recess. 100

105 In testimony whereof we have hereunto set our hands.

U SHERMAN AVERY.
ALBERT K. TROUT.
